No. 735,318.

PATENTED AUG. 4, 1903.

G. C. TYUS.
RAILWAY SWITCH.

APPLICATION FILED MAY 4, 1903.

NO MODEL.

Fig. 1.

UNITED STATES PATENT OFFICE.

GEORGE C. TYUS, OF PORTLAND, ARKANSAS.

RAILWAY-SWITCH.

SPECIFICATION forming part of Letters Patent No. 735,318, dated August 4, 1903.

Application filed May 4, 1903. Serial No. 155,651. (No model.)

To all whom it may concern:

Be it known that I, GEORGE C. TYUS, a citizen of the United States, residing at Portland, Ashley county, State of Arkansas, have invented certain new and useful Improvements in Railway-Switches, of which the following is a specification.

My invention relates to certain new and useful improvements in railway-switches, and has especial reference to means of locking the switch-points against movement, thereby securing additional safety.

The object of my invention is to provide a new and efficient means of locking or holding the switch-point against movement, which object I accomplish as will be more fully hereinafter set forth in the drawings, specification, and claims.

In the drawings, Figure 1 is a plan view of a railroad-switch with my device attached, showing switch set for main line and locked against movement. Fig. 2 is a sectional view taken on the line II II of Fig. 1. Fig. 3 is a sectional view taken on the line III III of Fig. 1.

Referring now to the drawings, in which like numerals indicate the same or like parts in all the views, 11 are the track-rails; 22, the switch-points; 33, the switch-ties; 4, the head-block, and 55 the switch-rods connecting the switch-rails. 6 is one of these rods, known as the "No. 1" rod, and which extends out to one side of the track for connection to the switch-stand. (Not shown.) Attached to the rod 6 is a piece 7, having a rack-section 8 on its under surface. This piece 7 is connected to the switch-rod 9 and by that to the switch-stand (not shown) in the ordinary manner, the switch (reference being omitted to the lock 40 for the present) being thrown in the ordinary manner. A pinion 10 meshes with the rack 8 and is rotated by it when the switch is thrown. This pinion is fastened to a shaft 11, which rotates in bearings 12 and which carries a bevel-gear 14, mounted on a shaft 15, carried by suitable bearings or loops 16. Arms 17 extend outward from this shaft and carry each a locking-block 18. The pinion 10 and the gears 13 and 14 are preferably so proportioned that movement of the rack 8 sufficient

to throw the switch-points 2 for the side track will raise the locking-blocks 18 and turn them through about one hundred and eighty degrees until they again rest on the ties, but in a reversed position—*i. e.*, one away from the switch. The blocks 18 are provided with slots 19, which engage that switch-point which is away from the rail. They may be made to fit over this as loosely or as snugly as may be desired.

20 represents bars to hold the rack down against the gear 10.

If so desired, the pinion 10 may be slipped to one side on the shaft 11 or the gear 13 14 be disengaged, permitting the locking-blocks 18 to be moved independently of the switch. For this purpose I extend the shaft 15 and form a handle 21 thereon by which the device can be operated. By thus separating the lock from the switch-operating means I am enabled to lock the switch open or shut, while when it acts with the switch I can lock it only when it is set for main track.

22 is a lock by which the handle 21 can be locked to the head-block when so desired.

While I have shown the shaft 15 attached to one of the ties 3, it can by shortening the arms 17 be placed on the head-block itself, and when so placed preferably comes on one side of same instead of flat on top, as shown.

In operation when the switch is thrown in the usual manner the rack 8 operates the pinion 10 and this the bevel-gears 13 14 and through them the locking-block 18.

Having now fully described my invention, what I claim, and desire to secure by Letters Patent in the United States, is—

1. In a switch-locking device the combination with the switch-points, the switch-stand, and the switch-rod, of a shaft, arms extending outward from said shaft, locking-blocks on said arms, a bevel-gear on said shaft, a second bevel-gear, a shaft with a pinion thereon carrying said second bevel-gear and a rack attached to said switch-rod and meshing with said pinion, substantially as shown and described.

2. In a switch-locking device the combination with the switch-points, the switch-stand and switch-rod, of a shaft, arms extending

outward from said shaft, locking-blocks on said arms, a bevel-gear on said shaft, a second bevel-gear, a shaft with a pinion thereon carrying said second bevel-gear and a rack attached to said switch-rod and meshing with said pinion, and means of disengaging said pinion from said rack, substantially as shown and described.

In testimony whereof I have signed my name to this specification in the presence of two subscribing witnesses.

GEORGE C. TYUS.
